(57) **CLAIM**

I claim the ornamental design for a scraping massage tool, as shown and described.

DESCRIPTION

FIG. 1 is a front-right elevation view of a scraping massage tool showing my new design;
FIG. 2 is a top view thereof;
FIG. 3 is a bottom view thereof;
FIG. 4 is a right side view thereof;
FIG. 5 is a left side view thereof;
FIG. 6 is a front side view thereof; and,
FIG. 7 is a rear side view thereof.
